CAGE-STUD FOR SNAP FASTENERS

Harold J. Reiter, Chicago, Ill.

Application June 23, 1948, Serial No. 34,651

2 Claims. (Cl. 24—213)

1

The present invention relates to improvements in snap fastener parts and, more particularly, to the structure of a novel two-piece fastener part of a kind commercially known as a cage-stud.

Cage-studs of the kind with which the present invention is concerned constitute one part of a separable snap fastener installation. The cage-stud is affixed on one face of a piece of material by suitable means, such as by a post-rivet, and it is adapted to be received and resiliently held in a circular socket formed in an associated socket part secured to another piece of material. Because of the resiliency of the cage-like structure of the cage-stud, a rigid stud is arranged within the cage part to receive the post-rivet and to reinforce and prevent complete collapse of the cage part under external pressures. Such cage-stud structure necessitates an assembly of parts and heretofore, and for many years past, the stud part and the cage part have been joined into an integral structure by a third member consisting of an annular channel-ring which embraces the peripheral margins of both said parts.

A three-piece structure such as referred to hereinabove is objectionable from a manufacturing standpoint because of the high material and labor costs involved in the fabrication and assembly of the three parts. It is objectionable in use because the free inner edge of the channel-ring disposed on the bottom face of the assembly lends itself to cutting and tearing through the sheet on which the cage-stud is mounted. Also, the base flange of such a cage-stud has four thicknesses of material around its peripheral margin thus making the cage-stud unnecessarily thick and increasing the over-all dimensions of an installation which obviously should be kept at a minimum.

It is therefore an object of the invention to provide a novelly fabricated cage-stud which overcomes all of the known objectionable features present in cage-studs of the kind fabricated prior to the present invention.

Another object is to provide a two-piece cage-stud of novel construction.

Another object is to provide a novel cage-stud having a smooth bottom face.

Another object of the invention is to provide a cage-stud embodying such novel features of construction as will greatly reduce material and lend itself to complete automatic assembly.

Another object is to provide a novel cage-stud having a base flange of minimum material thickness.

Other and further objects of the present invention will be apparent from the following descrip-

2

tion and claims, and are illustrated in the accompanying drawing which shows one embodiment and the method of fabrication. Other embodiments of the invention, embodying the same principle, may be used, and changes may be made as desired by those skilled in the art, without departing from the spirit of the present invention and the purview of the appended claims.

In the drawing:

Fig. 1 is a side elevational view of a cage-stud installation embodying the features of the present invention, showing the mounting strip in section.

Fig. 2 is a plan view of the cage-stud.

Fig. 3 is a vertical central sectional view of the cage-stud, mounted.

Fig. 4 is a central sectional view of a partially formed stud-body.

Fig. 5 is a central sectional view of the stud-body after additional forming.

Fig. 6 is a central sectional view showing the stud-body and cage assembled, but unsecured.

Referring to the drawing, the improved cage-stud includes a circular peripherally flanged stud-body, generally indicated at 11, and a cage, generally indicated at 12. The stud-body is fabricated from a circular piece of sheet material, preferably brass, and is provided with an axial upstanding stud 13 and an upstanding peripheral flange 14. In the completed fastener installation, the stud 13 receives a post-rivet to be described hereinafter; consequently, it is formed on its upper closed end with an enlarged head 15. The head 15 preferably is formed after the stud 13 is initially shaped, as shown in Fig. 4, by bumping or otherwise striking the end of the stud with a suitable tool so as to shorten its over-all length and cause its circular wall, at the top, to bulge outwardly. The headed stud is best illustrated in Fig. 5, where it is to be observed that it now has a reduced neck portion 16 and the axial center 17 of its end is concaved slightly. If desired, the neck portion of the stud may be engaged between rollers and reduced in diameter to provide the enlarged head. However, the bumping operation for enlarging the stud head and providing a reduced neck is desirable because of the presence of the circular flange 14, which may hinder the entrance of the usual rollers necessary to roll the neck.

The cage 12 (Fig. 6) also is fabricated from substantially stiff sheet material and it includes a solid center area 18 having relatively wide fingers 19 of substantially uniform width throughout their lengths radiating therefrom circumferentially. The fingers are bowed downwardly

from the center area 18 to define a circumferentially broken circular cage wall 21, and their free ends then are flared outwardly radially in a common plane, as at 22. The cage 12, prefabricated as described hereinabove, then is nested over the headed stud 13, as shown in Fig. 6. It should be observed that the cage is of a size to fit freely over and remain out of contact with the headed stud, and that its peripheral margin, defined by the radially flared end portions 22, rests upon the circular area 23 of the stud-body.

After the cage 12 has been nested over the headed stud, the upstanding peripheral flange 14 is rolled inwardly downwardly tightly over the end portions 22 to anchor the cage 12 in place. The diameter of the inner circular edge of the downturned flange 14 may be substantially the same as or slightly less than the outside diameter of the unsecured cage at the juncture between the cage wall 21 and the end portions 22. As a consequence, the lower portion of said cage wall is deflected inwardly radially slightly, thus insuring a downwardly inwardly tapered circular side wall suitable for frictional engagement and detachable retention in an associated socket part (not shown). In the absence of such dimensional requirements, the cage wall 21 may be tapered during the initial forming operation.

The completed cage-stud is mounted on a sheet or strip of material 25 by being placed against one face thereof, as shown in Fig. 3. A post-rivet, including a post 26 and a circular base flange 27, is arranged on the other face of the strip or sheet in axial alignment with the cage-stud. Pressure then is applied to project the post 26 through the strip or sheet, which may or may not have been previously perforated, and into the stud 13. As continued pressure is applied, the free end of the post-rivet 26 is distorted and flared outwardly radially into tight clinching engagement with the inside surface of the enlarged stud-head 15. At this time, the circular base of the cage-stud and the circular base flange 27 of the post-rivet are in tight clamping engagement, with the strip or sheet 25 therebetween.

The cage-stud described hereinabove is very sturdy in its construction and, because of the simplicity of assembly and the reduction in the number of parts previously necessary in an article of this character, it is very inexpensive to manufacture from the standpoint of material and labor required. It should be understood that the entire fabrication and assembly may be accomplished by continuous uninterrupted machine operations. For example, the cage and the stud-body may be fabricated by separate forming machines and conveyed automatically to hoppers or guides for delivery to a machine for assembling the two parts automatically. Such automatic delivery and assembly of prior art three-piece cage-studs has been economically impossible because of the difficulty in coordinating and positioning the three parts necessary for their fabrication. Also, the present cage-stud has a base

flange of minimum material thicknesses and the bottom face of the base flange is smooth, as distinguished from the channel-ring type of stud, so that tearing or cutting of the mounting strip or sheet is avoided. Consequently, a fastener installation which includes a cage-stud of the kind disclosed herein is capable of longer and more satisfactory service because of its durable structure and because it is less likely to tear out of its mounting when subjected to the stresses and strains of ordinary use.

Although an exemplary embodiment of the device of the invention has been illustrated and described in detail, it should be understood that the invention is capable of modification in detail without departing from the spirit of the invention and the scope of the appended claims.

I claim:

1. A snap fastener cage-stud comprising a flat circular base having an upstanding axial stud, an inverted cup-shaped cage of resilient material nested over said stud, said cage having its side walls defined by circumferentially spaced fingers of substantially uniform width throughout their lengths extending downwardly from the center of the cage, the fingers being spaced from the axial stud and having their free terminal portions extending radially and seated on and terminating short of the periphery of the flat circular base, and a peripheral flange integral with said circular base overlying said free terminal portions to retain the cup-shaped cage in place.

2. A snap fastener cage-stud comprising a flat circular base having an upstanding axial stud, an inverted cup-shaped cage of resilient material nested over said stud, said cage having its side walls defined by circumferentially spaced fingers of substantially uniform width throughout their lengths extending downwardly from the center of the cage, the fingers being spaced from the axial stud and having their free terminal portions extending radially and seated on the flat circular base and a peripheral flange integral with said circular base overlying said free terminal portions to retain the cup-shaped cage in place.
